(57) **CLAIM**

The ornamental design for a electric fly swatter, as shown and described.

DESCRIPTION

FIG. 1 is a perspective view of the electric fly swatter showing my new design;

FIG. 2 is a another perspective view of the electric fly swatter showing my new design;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof.

FIG. 9 is a perspective view thereof with an attachment of a stand.

FIG. 10 is a perspective view thereof with an attachment of a stand; and,

FIG. 11 is a partial enlarged view of portion 11 in FIG. 1. The broken line showing of portions of the electric fly swatter are included for the purpose of illustrating only and form no part of the claimed design.
